[57] CLAIM

The ornamental design for a cabinet contained folding table, as shown and described.

DESCRIPTION

FIG. 1 is a front elevational view of a cabinet-contained folding table showing our new design, shown in a fully closed position;

FIG. 2 is a right side elevational view thereof, shown in a fully opened position, the left side being a mirror image of that shown;

FIG. 3 is a top plan view thereof;

FIG. 4 is a front elevational view thereof;

FIG. 5 is a rear elevational view thereof, shown in a fully closed position;

FIG. 6 is a bottom plan view thereof;

FIG. 7 is a top, front, and left side perspective view thereof;

FIG. 8 is a rear elevational view thereof;

FIG. 9 is a front elevational view of an alternate embodiment thereof, the only difference residing in the back wall of the cabinet portion; and,

FIG. 10 is a rear elevational view of the alternate embodiment thereof, shown in a fully closed position.
